UNITED STATES PATENT OFFICE.

JOHN B. COXON, OF KOKOMO, INDIANA, ASSIGNOR TO KOKOMO SANITARY POTTERY COMPANY, OF KOKOMO, INDIANA.

DESIGN FOR A CLOSET TANK.

Application filed September 21, 1926. Serial No. 19,137. Term of patent 14 years.

To all whom it may concern:

Be it known that I, JOHN B. COXON, a citizen of the United States, residing at Kokomo, in the county of Howard and State of Indiana, have invented a new, original, and ornamental Design for a Closet Tank, of which the following is a specification, reference being had to the accompanying drawing, forming a part thereof.

The dominant feature of the ornamental design is the molding which is located at the bottom edge of the tank, which extends outwardly beyond the front side, the narrow

beveled corners and the lateral sides of the tank, and which has a vertical front face and inclined upper and lower faces.

Figure 1 is a front elevation of a closet tank, showing my new design,

Figure 2 is a top plan view of the same,

Figure 3 is an end elevation of the tank, and

Figure 4 is a perspective view of the tank.

I claim:

The ornamental design for a closet tank, as shown and described.

JOHN B. COXON.
